DESIGN FOR A GARMENT CONNECTOR

Paul Sanford, North Hollywood, Calif.

Application May 4, 1946, Serial No. 129,339

Term of patent 3½ years

(Cl. D17—3)

To all whom it may concern:

Be it known that I, Paul Sanford, a citizen of the United States, residing in North Hollywood, in the county of Los Angeles and State of California, have invented a new, original, and ornamental Design for a Garment Connector, of which the following is a specification, reference being had to the accompanying drawing, forming part thereof.

Fig. 1 is a face view of a garment connector, showing my new design.

Fig. 2 is a side elevational view.

I claim:

The ornamental design for a garment connector, substantially as shown.

PAUL SANFORD.
